UNITED STATES PATENT OFFICE.

JOHN RAPHAEL ROGERS, OF BROOKLYN, NEW YORK, ASSIGNOR TO MERGENTHALER LINOTYPE COMPANY, A CORPORATION OF NEW YORK.

TYPOGRAPHICAL COMPOSING-MACHINE.

1,076,064.

Specification of Letters Patent.

Patented Oct. 21, 1913.

Application filed January 24, 1912. Serial No. 673,092.

To all whom it may concern:

Be it known that I, JOHN RAPHAEL ROGERS, a citizen of the United States, and a resident of Brooklyn, county of Kings, 5 and State of New York, have invented a new and useful Improvement in Typographical Composing-Machines, of which the following is a specification.

My invention relates to typographical 10 composing machines, such as linotype machines of the general organization represented in Letters Patent of the United States, No. 436,532, to O. Mergenthaler, wherein circulating matrices are released 15 from a magazine in the order in which their characters are to appear in print and then assembled in line, together with expanding spacers, the composed line transferred to the face of a mold, the mold filled with molten 20 metal to form a slug or linotype against the matrices which produce the type characters thereon, and the matrices thereafter elevated and returned through a distributing mechanism to the magazine or magazines 25 from which they started.

More particularly, the invention relates 30 to that class of typographical machines in which are employed type or matrices provided with two or more characters, and a switch or equivalent device by which the position of the type or matrices may be varied so that each will present one or another of its characters in the line, as demanded. Such a combination is disclosed 35 in U. S. Letters Patent, No. 547,633, to P. T. Dodge, and my illustrated construction in many particulars corresponds thereto, but with certain changes and variations as will be subsequently set forth more specifically.

40 The principal generic distinction is that I am enabled to compose the type or matrices outside of the assembler proper at different levels and then transfer them thereto from such levels.

45 The means for accomplishing the above object are illustrated in the accompanying drawings in preferred form by way of example and as applied to a linotype machine, but obviously many changes and variations 50 may be made therein and in their mode of application without departure from the scope of the invention; and generally speaking, I desire it to be understood that I do not limit myself to any specific form or em-

bodiment except in so far as such limitations are specified in the claims. 55

Referring to the drawings: Figure 1 is a front view of part of a linotype machine having my invention applied thereto; Fig. 2 is a perspective view on an enlarged scale 60 of a portion of the assembling devices detached; Fig. 3 is a vertical sectional view, taken approximately on the line 3-3 in Fig. 2; Fig. 4 is a vertical section through the first elevator, mold and pot mouth, 65 showing the parts in casting position; Fig. 5 is a transverse vertical section through the assembler, taken substantially on the line 5-5 in Fig. 6; Fig. 6 is a longitudinal vertical section through the assembler, 70 taken substantially on the line 6-6 in Fig. 5; and Fig. 7 is a view of a plural-character matrix.

Referring to Fig. 1, the matrices are released from the magazine A by the manipulation of the keyboard A¹ and delivered to the assembler belt A². From the belt they pass to the device G, the particular construction of which will be subsequently described, and thence to the assembler B, the 75 customary spacers being inserted in the line during composition. The assembler B is then elevated by the manipulation of the handle B², mounted upon the rock shaft B³, which also carries the arm B⁴, connected 80 by the link B⁵ to the assembler. The elevation of the assembler carries the line between the fingers M and N, whereby it is shifted through the intermediate channel O to the first elevator C. The elevator C then 85 descends and the assembled line is brought to the casting position in relation to the mold D (see Fig. 4), and the molten metal is injected from the pot mouth D¹ to form the slug or linotype. After the casting operation, the elevator C rises in position to deliver the line to the upper transfer channel E wherein the spacers are freed from 90 the matrices and transferred to their magazine Y¹, the matrices being raised by the second elevator (not shown) for distribution. 95

All of the devices so far described, except as otherwise indicated, are or may be of the ordinary construction as disclosed 105 in the patents before referred to or in the commercial linotype machine.

In the form illustrated and described, I

have shown the employment of plural-character matrices X (see Fig. 7) having projecting ears X^1 and the V-shaped cut or notch X^2 . In order to bring one or another of the characters into operative position, I employ a switch device G , somewhat similar to that disclosed in the Dodge patent previously mentioned. This switch is vertically adjustable and is under the control of the hand lever G^2 connected to the switch by the link G^1 , a spring-pressed detent G^3 being provided to hold the parts in their different operative relations, all as in the said patent. It sometimes happens, in the use of such a switch, and chiefly arising from its form and immediate propinquity to the assembler, that the matrices are not properly delivered to the desired supporting ledges therein, this being due to improper deflection or rebound. To prevent such contingencies, I have formed the switch G with its guiding surface G^4 at a considerable distance from the assembler (see particularly Figs. 2 and 6), and with a ledge or supporting device G^5 projecting therefrom toward the assembler. Due to this construction and arrangement, the rebound and improper deflection of the matrices X are prevented, and further the actual composition of the matrices is secured outside of and away from the assembler, the matrices being subsequently transferred thereto from the supporting device G^5 by the means hereafter described.

The switch G comprises two separated parts (see also Fig. 3), between which the assembler slide H and the star wheel H^3 are located. The star wheel is rotated in the customary manner and its shaft or stud H^4 is mounted in vertical slots H^5 formed in the opposite sections of the switch G , so as to permit the adjustment of the latter to bring the supporting member G^5 into operative relation to the desired supporting ledges B^1 in the assembler B . The assembler slide H is formed with the finger H^1 to engage the forward end of the line during composition, it being held in proper engagement therewith by the spring H^2 (see Fig. 1) so as to constitute the customary yielding resistant. As the matrices and spacers are successively delivered between the star wheel H^3 and the finger H^1 , the latter is gradually moved forward into the assembler, and simultaneously the forward portion of the line is also transferred thereto.

In ordinary practice, I prefer to construct the supporting device G^5 only of such dimensions as to permit the assemblage thereon of a word of ordinary length, and it therefore results that when the composition of the line is completed, it will have been transferred to the assembler, with the exception of the last word or equivalent por-

tion of the line which still stands upon the supporting device G^5 . Before the assembler can be elevated and the line forwarded, it is necessary that this last portion be also transferred to the assembler, and to this end I have provided further devices which will now be described.

Also located between the two sections of the switch G is a transfer device or pusher J , which is similarly constructed in bifurcated form so as to straddle the star wheel H^3 , and formed with slots or recesses J^1 to receive the star wheel shaft H^4 and thus permit the movement of the pusher relatively thereto. Connected to the pusher J is the operating lever J^2 provided with the spring J^3 which normally tends to hold the pusher in its rearward or inoperative position. A second lever J^4 is loosely connected at one end to the operating lever J^2 and is so arranged that its opposite end is moved just before the elevation of the assembler B . The link B^5 , whereby the assembler B is elevated, is connected thereto by a lost-motion device, such as the pin-and-slot connection B^6 , in such manner that when the handle B^2 is actuated, the link B^5 is permitted a certain limited movement before it lifts the assembler. It is this preliminary limited movement of the link that acts to operate the pusher J and to transfer the line completely to the assembler before its elevation. The upper end of the link B^5 is provided with a spring-pressed pawl B^7 , which normally engages with the end of the lever J^4 . When the link first rises, the action of the pawl B^7 on the lever J^4 effects the turning of the lever J^2 and the forward movement of the pusher J to transfer the remaining word or matrices to the assembler. At this point the outer end of the lever J^4 has been tilted to a sufficient extent to permit the sliding detachment of the spring-pressed pawl B^7 therefrom, and the continued operation of the handle B^2 and the consequent movement of the link B^5 elevates the assembler and carries the line between the transfer fingers M and N , as previously described. As before set forth, the spring J^3 acts to retract the pusher J and to return the levers J^2 and J^4 . When the assembler then descends, the spring-pressed pawl B^7 is forced outwardly to clear the end of the lever J^4 and snaps thereunder into normal position. Fig. 2 shows the assemblage of the first part of a line and the manner in which the matrices X are introduced between the spring-controlled finger H^1 and the star wheel H^3 . Fig. 6 illustrates the operative movement of the pusher J whereby the latter part of the composed line is transferred to the assembler.

As previously stated, I have shown my improvements in preferred form by way of example, but obviously there will be many

changes and variations therein and in their mode of application, which will suggest themselves to those skilled in the art and still be comprised within their spirit.

5 Having thus described my invention, its construction and mode of operation, what I claim and desire to secure by Letters Patent of the United States is as follows:

1. In a typographical composing machine 10 comprising plural letter type or matrices, the combination of the assembler provided with means to support them at a plurality of levels, and means for supporting them outside of the assembler at a corresponding plurality of levels, together with assembling devices to deliver the type or matrices to the outside supporting means at any level.

2. In a typographical composing machine comprising plural letter type or matrices, 20 the combination of the assembler provided with means to support them at a plurality of levels, means for supporting them outside of the assembler at a corresponding plurality of levels, and assembling devices 25 to deliver the type or matrices to the outside supporting means at any level, together with further means for transferring the outside matter to the assembler.

3. In a typographical composing machine 30 comprising an assembler, the combination of means for supporting the type or matrices at a plurality of levels both inside and outside of the assembler, and assembling devices to deliver the type or matrices 35 to the outside supporting means at any level, together with further means for transferring the outside matter to the inside supporting means.

4. In a typographical composing machine 40 comprising plural letter type or matrices, the combination of the assembler provided with means to support them at a plurality of levels, means for composing them at corresponding levels outside of the assembler, 45 means for gradually transferring the line to the assembler as it increases in length, and means for finally transferring to the assembler the outside portion.

5. In a typographical composing machine 50 comprising plural letter type or matrices, the combination of the assembler provided with means to support them at a plurality of levels, means for composing them partly inside and partly outside of the assembler 55 at said levels, the outside portion being less

than the normal length of line, and means for moving the outside portion into the assembler.

6. In a typographical composing machine comprising plural letter type or matrices, 60 the combination of the assembler adapted to receive a full line thereof and to support them at a plurality of levels, means to compose less than the full line outside of the assembler at corresponding levels, a star 65 wheel to transfer the line gradually to the assembler as composition progresses, and means to transfer the remaining outside portion to the assembler.

7. In a typographical composing machine 70 comprising plural letter type or matrices, the combination of the assembler provided with means to support them at a plurality of levels, supporting devices to permit their composition outside of the assembler at a 75 corresponding plurality of levels, and means to transfer a portion thereof gradually to the assembler and the remaining portion at one time thereto.

8. In a typographical composing machine 80 comprising plural letter type or matrices, the combination of the assembler provided with means to support them at a plurality of levels, and means for supporting them outside of the assembler, the said outside 85 supporting means being adjustable to permit composition at any selected level, together with assembling devices to deliver the type or matrices to the outside supporting means in any of their adjusted positions. 90

9. In a typographical composing machine comprising plural letter type or matrices, the combination of the assembler provided with means to support them at a plurality of levels, and means for supporting them 95 outside of the assembler, the said outside supporting means being adjustable so as to be set in operative relation to any selected one of the supporting means in the assembler, together with assembling devices to deliver the type or matrices to the outside supporting means when set in any of their operative relations. 100

In testimony whereof I hereunto set my hand this 20th day of January, 1912, in the 105 presence of two attesting witnesses.

JOHN RAPHAEL ROGERS.
